SECTIONAL BOILER

Norwood Achey, Rossville, Ga.

Application April 15, 1946, Serial No. 662,387

2 Claims. (Cl. 122—225)

1

This invention pertains to boilers and has more particular reference to boilers of the sectional type.

Sectional type boilers usually comprise a front and a back section with any number of intermediate sections, depending upon the size and capacity of the boiler. Such boilers are usually made of cast iron and may be shipped in knock-down form and assembled at the place of installation. Such construction permits ready removal and replacement of burnt-out or defective sections of the boiler, which, in the case of boilers made of cast iron, is frequently required.

One object of the present invention is to provide a boiler having a front and a back section and one or more intermediate sections in which all sections are made of flat steel plate welded together.

Another object of the invention is to provide a sectional boiler having a large heating surface, no point of which is contacted by fire or heated gases without being water backed.

Another object of the invention is to provide a sectional boiler in which the heated gases make three longitudinal passages through the boiler, whereby the heat loss up the stack or chimney is reduced to a minimum.

Another object of the invention is to provide a sectional boiler that is simple and inexpensive to construct, economic and efficient in operation, and readily adapted to burn either coal, wood or liquid fuel.

A further object of the invention is to provide a sectional boiler made in sections that can be easily handled by two persons and moved through ordinary doorways.

A further object of the invention is to provide a sectional boiler in which the sections are held together by outside headers.

Other objects and advantages of the invention will appear in the specification, when considered in connection with the accompanying drawings, in which:

Fig. 1 is a perspective view of the boiler as viewed from the front left hand side;

Fig. 2 is a front elevation view of the boiler;

Fig. 3 is a vertical cross sectional view, taken on the line 3—3 of Fig. 2;

Fig. 4 is a front view of an intermediate section;

Fig. 5 is a side view of the intermediate section shown in Fig. 4;

Fig. 6 is a rear view of the back section;

Fig. 7 is a front view of the back section;

2

Fig. 8 is a vertical sectional view, taken on the line 8—8 of Fig. 7;

Fig. 9 is a vertical sectional view, taken on the line 9—9 of Fig. 7;

Fig. 10 is a horizontal sectional view, taken on line 10—10 of Fig. 7;

Fig. 11 is a front view of the front section;

Fig. 12 is a rear view of the front section;

Fig. 13 is a horizontal sectional view, taken on line 13—13 of Fig. 12;

Fig. 14 is a horizontal sectional view, taken on line 14—14 of Fig. 12; and

Fig. 15 is a vertical sectional view, taken on line 15—15 of Fig. 12.

15 In Fig. 1 there is shown a perspective view of a boiler constructed in accordance with the present invention. The boiler comprises a front section 10, a rear section 11, and a plurality of intermediate or mid-sections 12, mounted on a base 13. Each section of the boiler and the base are preferably made of flat sections of sheet steel welded together.

A front header 14 is mounted on top of the boiler and comprises a drum 15 having a plurality of depending flanged nipples 16, secured thereto as by welding. The drum and the nipples are preferably made of steel pipe. The top of the drum is provided with the usual outlets,

20 including a gauge connection 17, safety valve connection 18 and risers 19 and 20 for connection to a hot water or low pressure steam heating system. All of these outlets are preferably made of steel pipe welded to the drum and have threaded openings.

25 Bottom headers 21 are located on each side of the boiler, near the bottom thereof, and each comprises a drum 22 having a row of horizontally extending flanged nipples 23 secured thereto, preferably by welding. The drums 22 and 30 the nipples 23 are preferably made of steel pipe.

An equalizing pipe 24 connects the top header and the right hand bottom header. The front, back and each of the mid-sections are provided with a flanged riser 25 connected to one of the

45 flanged nipples 16 extending downwardly from the top header and a pair of horizontally extending flanged nipples 26, one located on each side thereof and being connected to one of the nipples 23 projecting from the adjacent bottom header. The risers 25 and the nipples 26 are preferably made of steel pipe and are secured to their respective sections preferably by welding.

50 One or more inlet connections 27 are mounted on the bottom header and are connected to the heating system. These connections are prefer-

ably made of steel pipe having a threaded opening and are secured to the bottom header, preferably by welding.

A smoke hood 28, preferably made of sheet steel, is mounted on the upper rear end of the back section and is secured thereto preferably by welding, one open end of the smoke hood communicating with the flue passage through the boiler and the other open end being adapted to be connected to a chimney or stack.

The base 13 of the boiler is preferably made up of steel plates set on edge and tack welded together, forming a hollow space within and underneath the boiler. Angle irons 29 are welded around the top edges of the base to help support the boiler sections.

A boiler constructed in accordance with the present invention is readily adaptable to burn coal, wood, or liquid fuel. In the particular embodiment shown, an automatic stoker is provided. The stoker retort 30 is located within the base of the boiler and the space between the walls of the base and the stoker retort is bricked up with fire brick 31. In so far as the present invention is concerned, the stoker may be of any conventional type. The stoker shown comprises a retort 30 located within the space defined by the upright walls of the base 13; a fuel feed tube 32 having a rotary feed screw 33 mounted therein and extending outwardly through an opening provided in the front of the base 13; a casing 34 mounted in the outer end of the feed tube for housing the operating mechanism for the screw 33; a fuel hopper 35 mounted on the feed tube; a tube 36 for supplying air to the retort; and an ash removal tube 37.

In Figs. 3, 11, 12, 13, 14 and 15 there is shown the details of the front section with the riser connections to the top and bottom heads omitted. The front section is a hollow sectional structure having a substantially rectangular shape and comprises a top plate 36, side plates 37 and 38, bottom plate 39 and a front plate 40, all made of flat sheet steel welded together. The front plate 40 is provided with a spaced pair of horizontally aligned openings 41 near the top, to provide access to the flue passages, each opening being provided with a hinged door 42, and a centrally located opening 43 near the bottom to provide access to the combustion chamber, the opening being provided with a hinged door 44. A flat horizontal plate 45 of sheet steel is located within the hollow section and extends transversely thereof at a point aligned with the lower edges of the openings 41. Four triangular shaped communicating water passages 46, 47, 48 and 49, surrounding the opening 43, are formed in the lower half of the front section by means of four trapezoidal-shaped flat steel plates 50, 51, 52 and 53, each plate having its front edge welded to the front plate 40, its side edges welded to the contiguous edges of the adjacent plates and its rear edge welded to the rear edges of the side plates 37, 38, bottom plate 39 and the plate 45.

A triangular shaped water passage 54 is formed across the top of the front section by means of a trapezoidal-shaped plate 55 having its front edge welded to the front plate 40 and its rear edge welded to the rear edge of the top plate 36. Triangular shaped water passages 56 and 57 are formed along the upper sides of the front section by means of trapezoidal-shaped plates 58 and 59, each having its front edge welded to the front plate 40 and its rear edge welded to the rear edge of the adjacent side plates 37 and 38. The upper

edges of the plates 58 and 59 are welded to the contiguous side edges of the plate 55 and the lower edges of plates 58 and 59 are welded to the transversely extending plate 45. A rectangular shaped water passage 60 is formed on the inner surface of the front plate between the openings 41 and connects the upper triangular shaped water passage 54 and the triangular shaped water passage 47 in the lower portion of the hollow section. A plurality of stay bolts 61 may be welded to the front and rear plates of the water passages if considered desirable.

The intermediate or mid-sections are of identical construction. In Figs. 4 and 5 there is shown the details of an intermediate section with the riser connections to the top and bottom headers omitted. Each intermediate section is a hollow sectional structure made up of flat sections of sheet steel welded together and comprises a substantially rectangular shaped hollow member 62 having hollow elongated rectangular shaped vertical legs 63 and 64 formed on each end, the hollow sections forming communicating water passages. The member 62 has four horizontal aligned spaced apart flue passages 65 formed therein.

In Figs. 6, 7, 8, 9 and 10 there is shown the details of the rear section with the riser connections to the top and bottom headers omitted. The rear section is a hollow sectional structure having a substantially rectangular shape and comprises a top plate 66, side plates 67, 68, bottom plate 69, front plate 70 and a back plate 71, all made of sheet steel welded together. The back plate 71 is formed with a spaced pair of horizontally aligned openings 72 and 73 near the top to provide an exit for the flue passages. The front plate 70 is of less width than the back plate 71 and has two spaced apart integral vertical extensions 74 and 75 formed on its upper edge. The side plates 67 and 68 are of identical construction and each comprises an elongated rectangular member having an integral triangular shaped upper end.

A pair of trapezoidal shaped plates 76 and 77 have their upper edges welded to the forward edge of the top plate 66 and their lower edges welded to the upper edges of the extensions 74 and 75, respectively, of the front plate 70, to form triangular shaped water passages 78 and 79.

A spaced pair of horizontally extending flue passages 80 and 81 are formed in the back section by means of vertical plates 82, 83, 84 and 85 and horizontal plates 86, 87, 88 and 89. These plates have their rear edges welded to the back plate 71 along the edges of the openings 72 and have their contiguous side edges welded to each other.

Triangular shaped water passages 90, 91 and 92 are formed along the outer sides and the bottom of the flue passages by means of trapezoidal shaped plates 93, 94 and 95. These plates have their rear edges welded to the edges of the recess formed in the front plate 70 by the extensions 74 and 75 and have their contiguous side edges welded together. The upper edges of plates 93 and 95 are welded to the side edges of plates 76 and 77.

A flat rectangular plate 96 having an elongated integral depending rectangular extension 97 forms the front wall of a rectangular shaped water passage 98 located centrally of the top of the back section and communicating with water passages 78 and 79. The upper edge of plate 96 is welded to the front edge of top plate 66, the side edges of plate 96 are welded to the front edges of plates 93 and 94. The bottom edges of

plate 96 and the side edges of extension 97 are welded to the contiguous front edges of plates 83, 84, 86 and 87. The bottom edge of member 97 is welded to the front edge of trapezoidal shaped plate 94, thus forming a vertical water passage 99 located between the flue passages 80 and 81 and communicating with the water passages 91 and 93. A plurality of stay bolts 100 may be welded to the front and back walls of the water space formed between the front plate 70 and the back plate 71, if considered desirable.

Vertically extending triangular shaped water passages 101 and 102 are formed on the outer ends of the back section by means of flat vertical plates 103 and 104. The plate 103 has its front edge welded to the front edge of side plate 67, its bottom edge welded to the bottom plate 69, its rear edge welded to the side edge of front plate 70 and its upper edge welded to the outer edge of plate 76. Plate 104 has its front edge welded to the front edge of side plate 68, its bottom edge welded to the bottom plate 69, its rear edge welded to the side edge of front plate 70 and its upper edge welded to the outer edge of plate 77. The bottom plate 69 is formed with forwardly projecting integral triangular shaped extensions on each end and has its edges welded to the contiguous bottom edges of the front plate 70, back plate 71 and plates 103 and 104, thus forming a water passage 105 extending across the greater portion of the back section.

Each section of the boiler, when constructed as above set forth, is of light weight and can be readily handled by two men. Also, due to their size and shape, they may be carried through ordinary sized doorways and passageways.

In assembling the boiler, the base is first assembled and the particular type of automatic stoker mounted therein. Then, the front, back and intermediate sections are mounted on the base. The top and bottom headers are then assembled on the boiler. The entire boiler is held together by the headers. The joints between the sections are preferably sealed on the outside with boiler putty to prevent escape of gas. In the event any one of the sections becomes defective it can be readily removed for repair and replacement.

A combustion chamber 106 is provided within the boiler, the lower portions of the front and back sections forming water backed front and rear walls, respectively, of the combustion chamber. The hollow vertical legs 63 and 64 of the intermediate sections form water backed side walls and the bottoms of the hollow members 62 of the intermediate sections form the water back top wall of the combustion chamber.

The heated gases of combustion pass rearwardly through the combustion chamber to the front wall of the back section, where they contact the forwardly and upwardly inclined plates 76 and 77 which direct them forwardly into the two outer flue passages 65 extending through the intermediate sections. The heated gases pass through the two outer flue passages to the front section, where they strike the front plate of the front section and are directed rearwardly into the two inner flue passages 65 extending through the intermediate sections. After passing through the intermediate sections, they pass through the flue passages 80 and 81 of the rear section and into the smoke box and thence to the chimney or smoke stack. This results in the heated gases of combustion making three pas-

sages through the boiler, thereby reducing the heat loss up the smoke stack to a minimum.

From the foregoing description, it will be seen that the improved sectional boiler of the invention embodies features making the boiler highly desirable from the standpoint of simplicity and economy of operation, efficiency of combustion and heat transfer, and compactness.

Obviously, the present invention is not restricted to the particular embodiment thereof herein shown and described. Moreover, it is not indispensable that all the features of the invention be used conjointly, since they may be employed advantageously in various combinations and sub-combinations.

What is claimed is:

1. A sectional steel boiler including a front, a back and a plurality of intermediate sections communicatively connected and enclosing a combustion chamber; said intermediate sections being hollow and having at least two spaced horizontally aligned registering openings extending therethrough forming flue passages, said openings having water backed walls; said front section being hollow and having an opening extending through its lower portion to provide access to said combustion chamber and having an elongated transverse pocket formed in its upper portion, said opening having water backed walls and being provided with a closure member, said pocket opening rearwardly and communicating with said flue passages and having its top, bottom and side walls water backed, the front wall of said pocket having openings therein to provide access to said flue passages for cleaning, said openings in said front wall being provided with closure members; said back section being hollow and having at least one flue passage having water backed walls extending therethrough and communicating with one of said flue passages through the intermediate sections and at least one elongated vertically extending pocket, said pocket being open in front and having water backed top, back and side walls and having its lower end opening into the combustion chamber and its upper end communicating with another of the flue passages through the intermediate sections; all of said sections being independent of each other and having external nipples at their top and bottom portions connected to outlet and return headers, respectively, and constituting the sole connections between said sections, whereby any of said sections may readily be removed and replaced without disturbing the other sections; the construction being such that the hot gases of combustion will be directed upwardly and forwardly through one of the flue passages in the intermediate sections into the pocket formed in the front section where they are directed inwardly and rearwardly through another of the flue passages in the intermediate section into and through a flue passage of the back section.

2. A sectional steel boiler including a front, a back and a plurality of intermediate sections communicatively connected and enclosing a combustion chamber; said intermediate sections being hollow and having four spaced horizontally aligned registering openings extending therethrough forming flue passages, said opening having water backed walls, said front section being hollow and having an opening extending through its lower portion to provide access to said combustion chamber and having an elongated transverse pocket formed in its upper portion, said

opening having water backed walls and being provided with a closure member, said pocket opening rearwardly and communicating with said flue passages and having its top, bottom and side walls water backed, the front wall of said pocket having openings therein to provide access to said flue passages for cleaning, said openings in said front wall being provided with closure members; said back section being hollow and having a horizontally spaced pair of flue passages having water backed walls extending therethrough and communicating with the two inner flue passages through the intermediate section and a spaced pair of elongated vertically extending pockets, each of said pockets being open in front and having water backed top, back and side walls and having its lower end opening into the combustion chamber and its upper end communicating with one of the outer flue passages through the intermediate sections; all of said sections being independent of each other and having external nipples at their top and bottom portions connected to outlet and return headers, respectively, and constituting the sole connections between said sections, whereby any of said sections may readily be removed and re-

placed without disturbing the other sections; the construction being such that the hot gases of combustion will be directed upwardly and forwardly through the outer flue passages in the intermediate sections into the pocket formed in the front section where they are directed inwardly and rearwardly through the two inner flue passages in the intermediate sections into and through the two flue passages of the back section.
